UNITED STATES PATENT OFFICE.

WILLIAM L. WALTON, OF ST. LOUIS, MISSOURI, ASSIGNOR TO WILLIAM H. O'BRIEN, ADAM G. TORRANCE, AND CHARLES W. WALTON, OF SAME PLACE.

COLLAPSIBLE CHICKEN-COOP.

SPECIFICATION forming part of Letters Patent No. 633,929, dated September 26, 1899.

Application filed December 20, 1898. Serial No. 699,850. (No model.)

To all whom it may concern:

Be it known that I, WILLIAM L. WALTON, a citizen of the United States, residing at St. Louis, State of Missouri, have invented certain new and useful Improvements in Collapsible Chicken-Coops, of which the following is a full, clear, and exact description, reference being had to the accompanying drawings, forming a part hereof.

My invention has relation to improvements in chicken-coops; and it consists in the novel arrangement and combination of parts more fully set forth in the specification and pointed out in the claim.

In the drawings, Figure 1 is a top plan of the coop, but with the top cover removed. Fig. 2 is an end elevation thereof. Fig. 3 is a longitudinal section on line 3 3 of Fig. 1 after the end walls, however, have been folded down. Fig. 4 is a section on the same line after, however, both the end walls and side walls have been folded down against the bottom, the plane of section just skipping the edge of the side wall thus folded, and thus leaving the edge in elevation. This view also shows by dotted lines the position the removable cover occupies in the packing of the folded coops during shipment. Fig. 5 is a top plan of the coop with the cover in place, and Fig. 6 is a section on line 6 6 of Fig. 5 of only the upper portion of the coop.

The object of my invention is to construct a folding or knockdown chicken-coop whereby the same can be folded or knocked down to a compact form when not in use or when shipped empty, whereby the freight charges can be materially reduced by reason of the less space the same occupies in its folded form. In detail the invention may be described as follows:

Referring to the drawings, 1 represents the bottom of the coop, and 2 and 3, respectively, the end and side inwardly-folding slatted walls or leaves thereof. The inner leaf of each of the hinges 4, by which the end walls are secured to the bottom, rests in a depression 5, located adjacent to the edge of the said bottom, the depth of the depression being substantially equal to the thickness of the hinge-leaf, whereby as the end wall 2 is closed its

inner surface folds flush with the upper surface of the bottom—that is to say, it folds so as to rest with its entire surface on such bottom. Disposed along the terminal edges of the side walls are inwardly-projecting blocks 6, adapted to interlock between the adjacent ends of any two parallel horizontal slats of which the end walls are composed, the dotted position of the side walls in Fig. 2 showing the said blocks just before they have become interlocked with the end walls of the coop, the side walls being sprung outwardly sufficiently to effect such interlocking. The side walls are pivoted on top of longitudinal strips or stringers 7, disposed along the lateral edges of the bottom, the said stringers being of sufficient height to enable the said side walls to fold freely over the end walls when the latter have been swung to their closed position. (See Fig. 4.) To prevent the end walls from accidentally closing after becoming interlocked with the side walls, as aforesaid, the latter have secured thereto along their vertical terminal slats at points adjacent to the upper ends thereof abutting blocks 8, against which the upper ends of the terminal vertical slats of the said end walls bear, as best seen in Fig. 1. It is of course to be understood that each wall is made up of two series of slats, one running horizontally and the other at right angles thereto, as usual in coops of this description. In order to permit the side walls to close snugly over and upon the end walls when the coop is knocked down, I provide suitable recesses 9 in the slat of the end walls which lie adjacent to the hinge-line to permit the abutting blocks 8, carried by the side walls, to escape such slat, for otherwise the side wall could not rest with its entire surface against such end wall after the latter had been folded to its closed position.

The slatted cover 10, which is removable, is provided with a metallic transversely-disposed plate or strip 11, having depending arms or straps 11' adapted to engage the rotatable eyebolts 12 or other equivalent locking devices to temporarily secure such cover to the body of the coop. To effect a rigid connection between the cover and walls of the coop, I provide the underside of the outer

side slats of the cover with strips 13, which are of such length as to frictionally engage the inner surfaces of the side walls of the coop at points between the terminal and middle vertical slats of the latter. (See dotted position of said strips in Fig. 5.) As in most covers in this type of coop, the present one is provided with a removable slat 14, retained in place by suitable guide-strips 15 for the removal of the fowl after such slat has been withdrawn sufficiently for the purpose. (See dotted position in Fig. 5.)

When the coop is knocked down or collapsed, the cover is placed on top of the folded leaves or walls, the straps 11 thereof being secured to the bottom by rotatable eyebolts 16, projecting from the middle of the side edges thereof, the said eyebolts being passed through the slotted ends of the straps and then turned at an angle to the length of the slots to properly lock the cover to the coop so folded. In this way the device can be shipped in a compact form, thus taking up a minimum amount of room. The cover thus secured to the collapsed coop is shown in dotted lines in Fig. 4.

It is apparent that minor changes can be made in the device without departing from the spirit of my invention.

Having described my invention, what I claim is—

A coop having a suitable bottom, slatted end walls or leaves having hinges one leaf of each of which is mounted in a suitable depression in the bottom, whereby the said end

walls will fold with their full surface against the bottom, suitable recesses cut in the end walls adjacent to their hinge-lines, stringers disposed along the longitudinal edges of the bottom and raised a suitable distance above the same, side walls hinged along said stringers, blocks carried at the opposite edges of the side walls and adapted to interlock with the slats of the end walls, blocks secured along the inner surfaces of the side walls against which the upper portions of the end walls are adapted to abut, thereby preventing accidental closing of the end walls, the abutting blocks carried by the side walls being adapted to enter the recesses formed along the hinge-lines of the end walls, a cover having a plate provided with depending straps or arms, means carried by the walls of the coop for securing said straps when the cover is in place, fastening devices carried by the middle of the side edges of the bottom for similarly securing said straps when the coop is knocked down, and a series of strips disposed along the under surface of the cover adjacent to the edges thereof, said strips serving to frictionally engage the adjacent inner surfaces of the side walls of the coop between the terminal and middle vertical slats thereof, substantially as set forth.

In testimony whereof I affix my signature in presence of two witnesses.

WILLIAM L. WALTON.
